UNITED STATES PATENT OFFICE.

FRED W. BARHOFF, OF HARTFORD, CONNECTICUT, ASSIGNOR TO THE UNITED STATES FIBER LEATHER COMPANY, OF HARTFORD, CONNECTICUT, A CORPORATION OF CONNECTICUT.

PRESS.

No. 893,892.

Specification of Letters Patent.

Patented July 21, 1908.

Application filed October 9, 1907. Serial No. 396,626.

To all whom it may concern:

Be it known that I, FRED W. BARHOFF, a citizen of the United States, residing at Hartford, in the county of Hartford and State of Connecticut, have invented a new and useful 5 Press, of which the following is a specification.

This invention relates to a press which is designed to withdraw water from and knit 10 and solidify sheets of fibrous pulpy composition.

The object of the invention is to provide a comparatively simple power press which can be made to squeeze out and at the same time 15 suck water from and air through a mass of pulpy fibrous material, such as is used in the formation of thick sheets of pulp board, binders board and board containing more or less leather fiber known as leather-board, so as to 20 knit the fiber and produce a strong, hard sheet.

The machine which is illustrated is designed to receive a mold containing pulp and by hydraulic or pneumatic pressure force a 25 platen down on the top so as to compress the pulp and assist the escape of the water by squeezing, and draw down a piston beneath the mold and suck water from the pulp, and also if desired force air through the pulp so as 30 to increase the outflow of water, whereby thick masses of wet pulp can be relieved of free moisture in such manner as to knit the fibers and be solidified very rapidly and uniformly.

35 Figure 1 of the accompanying drawings shows a side elevation of a press that embodies the invention. Fig. 2 shows a central section on larger scale of the upper part of the press. Fig. 3 shows a similar section on 40 the same scale of the lower part of the press. Fig. 4 is a transverse section on the plane indicated by the dotted line $x-x$ looking upwardly. Fig. 5 is a similar section on the same plane looking downwardly. Fig. 6 45 shows a plan of the bed. Fig. 7 shows an edge view of the bed. And Fig. 8 shows a section of the bed.

The machine illustrated stands upon a base 1. Mounted on this base is a cylinder 2. The lower end of the cylinder is closed by the base and the upper is closed by a head 3. There is an opening 4 through the side near

the bottom of the cylinder and an opening 5 through the side near the top of the cylinder, these openings being designed to be piped to 55 the source of power which is employed to move the piston 6, that is fitted in this cylinder, and has a rod 7 which extends through a suitably packed stuffing box 8 on the head. Set on the upper end of this lower power cylinder 60 is a larger cylinder 9 which is open at both ends, and in this cylinder is a suction piston 10 that is attached to the rod 7 of the lower power piston.

Mounted upon the upper end of the intermediate or suction cylinder is the bed 11. This bed is preferably rectangular in outline and has its bottom formed of grate bars. The bed may have other forms of openings however, it is only essential that it be perforated so that the downward movement of the suction piston will draw air through it without pulling down the mold. In the upper face of the bed around the edges are 65 grooves containing packings 12 which extend on all sides so as to make a tight joint with the bottom of the mold frame 13 which is designed to receive the mold containing the pulp to be dried and pressed.

Posts 14 are arranged to extend upwardly 70 from the top of the bed and mounted on the upper ends of these posts is a cylinder 15, this cylinder having outwardly extending arms with recesses for receiving the upper 75 ends of the posts. The top of this upper cylinder is closed by a head 16 and the bottom by a head 17 provided with a stuffing box 18. There is an opening 19 through the side near the lower end of the cylinder and an opening 20 through the side near the upper end of the cylinder, these openings being 80 designed to be piped to the source of power which is utilized to move the piston 21 which is fitted in the cylinder. The piston rod 22 from this upper power piston extends 85 through the stuffing box and is connected with the platen 23 which is shaped to fit into the mold frame. This platen is desirably formed of a frame with grate bars, but it may be perforated in other ways. Extending 90 upwardly from one side of the platen through an opening in the frame of the upper cylinder is a rod 24 which is utilized to guide the platen in its movements and prevent it 95 100

from turning. A hood 25 can be arranged over the platen so as to inclose this mold and this hood may be piped to a source of compressed air, whereby the flow of water from the pulp, when it is being solidified, may be increased by the flow of air under pressure.

The piping for the upper and lower power cylinders may be connected with any source of hydraulic, pneumatic or steam power, and 10 the squeezing and suction pistons may be operated co-incidently or independently as desired, and the drying, knitting and solidification of the mass may be facilitated by the application of compressed air at the 15 proper time.

A mold containing pulp, which may be a mixture of leather, rags and paper, beaten to the necessary consistency, is placed in the mold frame and the power admitted to the 20 upper and lower pistons so that the upper piston will force the platen down upon the pulp in the mold and compress it, and the lower piston will draw down the suction piston and suck out water and moisture from the 25 pulp while it is being compressed. The upper cylinder can alone be used if desired for compressing the pulp and squeezing out water, or the lower cylinder can alone be used for sucking water out of the pulp, or 30 both pistons can be used at practically the same time for sucking out the water and compressing the pulp. The water which is removed in this way can escape through the bottom of the suction cylinder which is left 35 open for that purpose. The flow of water induced by the suction of the suction piston assisted by the flow of compressed air through the mass knits together the fibers in such manner as to produce tough sheets.

40 With this press thick wet masses of pulp can be quickly compressed and hardened, the free moisture being removed and the fibers knitted, so that the sheet formed will be compact, strong and substantially dry.

45 When the compression and suction is completed power is so applied as to lift the platen and the suction piston and then another mold is slipped into the place pushing out the mold with the pulp that has been solidified and dried. After the pulp has been 50 compressed, if desired, while the platen is down steam or other hot fluid can be admitted below the mold through the opening 26 in the top of the suction cylinder for heat-

ing, hardening and possibly vulcanizing the 55 mass.

The invention claimed is:

1. A press for solidifying pulp having a 60 perforated bed, a suction piston beneath the bed, and means for moving the suction piston toward and from the bed, substantially as specified.

2. A press for solidifying pulp having a 65 perforated bed, a suction piston below the bed, and a power piston connected with and designed to move the suction piston toward and from the bed, substantially as specified.

3. A press for solidifying pulp having a 70 perforated bed, a suction piston below the bed, means for moving the suction piston toward and from the bed, a platen above the bed, and means for moving the platen toward and from the bed, substantially as specified.

4. A press for solidifying pulp having a 75 perforated bed, a suction piston for drawing air through the bed, means for moving the suction piston, a platen movable toward the bed, and means for moving the platen toward and from the bed, substantially as specified.

80 5. A press for solidifying pulp having a perforated bed, a suction piston for drawing air through the bed, a power piston connected with and adapted to move the suction piston, a platen movable to and from the bed, and a power piston connected with and adapted to move the platen, substantially as specified.

85 6. A press for solidifying pulp having a 90 perforated bed, a suction piston beneath the bed, a power piston connected with and adapted to move the suction piston, a perforated platen movable toward and from the bed, and a power piston connected with and adapted to move the platen, substantially as specified.

95 7. A press for solidifying pulp having a 100 perforated bed, a suction piston for drawing air through the bed, means for moving the suction piston, a platen movable toward the bed, means for moving the platen, and means for forcing air down upon the bed, substantially as specified.

FRED W. BARHOFF.
